United States Patent Office

Des. 204,551
Patented Apr. 26, 1966

204,551

DOLL

Helen L. Unseth, 808 Park Plain Ave., Park Ridge, Ill.

Filed Oct. 14, 1965, Ser. No. 87,484

Term of patent 14 years

(Cl. D34—4)

FIG. 1 is a front perspective view of a doll embodying my new design; and

FIG. 2 is a rear perspective view thereof.

I claim:

The ornamental design for a doll, substantially as shown.
